UNITED STATES PATENT OFFICE

158,238

EXTERNAL BATTERY ADAPTER FOR
HEARING AIDS

Leland A. Watson, Minneapolis, Minn., assignor
to The Maico Company, Incorporated, Minne-
apolis, Minn., a corporation of Minnesota

Application March 1, 1948, Serial No. 144,853

Term of patent 3½ years

(Cl. D26—14)

To all whom it may concern:

Be it known that I, Leland A. Watson, a citizen of the United States, residing at Minneapolis, in the county of Hennepin and State of Minnesota, have invented a new, original, and ornamental Design for External Battery Adapters for Hearing Aids, of which the following is a specification, reference being had to the accompanying drawing, forming part thereof.

Referring to the drawing:

Fig. 1 is a plan view of an external battery adapter for hearing aids, showing my new design, a portion of the connecting cable thereof being broken away;

Fig. 2 is a bottom plan view of one of the battery plugs on an enlarged scale, illustrated at the right of Fig. 1;

Fig. 3 is a side elevational view of Fig. 2; and

Fig. 4 is a perspective view of Fig. 3.

The dominant features of the design reside in that portion shown in full lines in the drawings.

I claim:

The ornamental design for an external battery adapter for hearing aids, as shown and described.

LELAND A. WATSON.
